CLAIM

The ornamental design for shielding for a forage harvester, as shown and described.

DESCRIPTION

FIG. 1 is a top view of shielding for a forage harvester of the present design.

FIG. 2 is a right side view of the shielding of FIG. 1.

FIG. 3 is a left side view of the shielding of FIG. 1.

FIG. 4 is a front view of the shielding of FIG. 1; and,

FIG. 5 is a rear view of the shielding of FIG. 1.

The dashed lines shown in the figures represent environmental subject matter and form no part of the claimed design.
